CLAIM

The ornamental design for a window cutout for a package, as shown and described.

DESCRIPTION

FIG. 1 is a perspective view of a window cutout for a package, showing our new design;

FIG. 2 is a top view thereof;

FIG. 3 is a front view thereof;

FIG. 4 is a back view thereof;

FIG. 5 is a bottom view thereof;

FIG. 6 is a left view thereof; and,

FIG. 7 is a right view thereof.

The portions of the drawings shown in broken lines represent environmental structure and form no part of the claimed design.
